UNITED STATES PATENT OFFICE.

CURT WILLIBALD ALEXIS HANNEBOHN, OF BERLIN-CHARLOTTENBURG, GERMANY,
ASSIGNOR TO ALEXIS KELLNER, OF BERLIN-CHARLOTTENBURG, GERMANY.

MOTOR-CARRIAGE HOOD.

Application filed January 10, 1925, Serial No. 1,682, and in Germany December 20, 1923.

My invention relates to a motor-carriage hood having horizontally guided longitudinal kilt hoops. This hood is distinguished from the known ones essentially by the feature that the rear part of the two longitudinal tilt hoops is connected with the turnable column and with the bendable rule-joint or coach joints by a guide lever connection in such a manner that the longitudinal tilt 5 hoops are guided not only parallelly, but participate in the movement of the turnable column in conjunction with the bending movement of the rule-joint or coach-joint, which latter is bent automatically by means 10 of a spring acting in a telescope-tube and engaging the rotatory head of the rule-joint or coach-joint, as well as the foot-member of this joint, said automatic bending taking 15 place when the front hood tilt hoops are being lifted.

Collapsing the hood is effected after the front longitudinal tilt hoops have been lifted, preferably and most conveniently by a pull in rearward direction. There are provided for this purpose one or several straps 20 which engage the front transverse tilt hoop and extend over the hood.

As it is unnecessary to provide a middle carrying rod for the hood, a particularly reliable hinge-joint must be provided between 25 the front and the rear parts of the longitudinal tilt hoops. This hinge-joint or hinge-connection is, according to this invention, so devised that the tilt hoops cannot bend 30 through when the hinge-members are directed downwardly, whereas when the hinge-members have been turned through 180°, the front longitudinal tilt hoop can be turned 35 upwardly upon that hinge.

The invention is illustrated diagrammatically and by way of example in the accompanying drawings, in which Figure 1 is a perspective illustration of a motor-carriage provided with my improved hood; which 40 is shown in closed state; Figure 2 is a longitudinal section through the closed hood, combined with a side-view of the appertaining mechanism, this figure being drawn to a greatly enlarged scale relatively to Fig. 1; Figure 3 is a side-view of the same mechanism, partly collapsed, and Figure 4 shows 45 it completely collapsed; Figures 5 and 6 are separate views of the tilt hoops in two positions, these figures being drawn to a still 50 more enlarged scale; Figure 7 is a separate

view of the hinge of the longitudinal tilt hoop, the hinge being shown in section; Figure 8 is a plan of this joint; and Figures 9 and 10 show details which are fully described hereinafter.

1 denotes the body of the carriage, 2 the rear part of the body; this part is shaped similarly to a box or chest, as usually, 3 denotes the angular body member of a hinge 4, to which is jointed a bar 5, the lower part 5a of which is bent angularly, as shown. 6 is a bell-crank lever which is pivoted to the column 5 and one end of which is connected with the upper part 8 of the rule-joint or coach-joint 8, 10 by means of a link 7. The members 8 and 10 of the rule joint or coach joint are connected with one another in known manner by a hinge 9 and can, therefore, be bent relatively to one another, and the member 10 is hinged at the point 11 to a fastening member 11. 12 denotes a telescope-tube spring which is jointed movably to the rule joint or coach joint member 10 at the point 12b and to an angular member 13 at the point 12a. The object of said telescope-tube spring is to bend the rule-joint or coach-joint automatically when a pressure is exerted on said angular member 13 which is hinged at the point 14 to a lateral projection of the rod 5.

The other leg of the bell-crank lever 6 is connected with another bell-crank lever 17 by means of a rod 16. The bell-crank lever 17 is pivoted to the body-member 18 which is firmly connected with the column 5. 19 denotes the pivot of said lever 17; this pivot serves also as a support for the longitudinal tilt hoop 20. This tilt hoop and the front tilt hoop 21 are connected with one another by a hinge 22 and by an arrangement and combination of rods resembling Nuremberg scissors. The members 23, 24 of the Nuremberg scissors are connected with one another by a bolt 25 and the member 23 is connected, besides, with the longitudinal tilt hoop 21 by the pivot 26. The rod 15 engages the scissor-member 24 between the pivots 25 and 27 whereby a pressure is exerted upon the angular member 13 when the front tilt hoop 20 is being lifted. The free ends of the scissor members 23 and 24 carry the transverse tilt hoops 28 and 29 upon which the hood 30 is mounted in known manner, whereas an arm 31 attached to the rear part of the hood 30 and connected movably with the hinge-mem- 100
105
110

ber 3 is provided for the proper exterior shape of the hood.

The angular member 13 carries the transverse tilt hoop 32. The middle support 5 shown in Fig. 2 has nothing to do with the invention and I abstain, therefore, from entering into details concerning it.

One strap 33 extends, or several straps 33 extend, longitudinally over the hood 30; they 10 may be coupled loosely with the hood by guide-loops (not shown) or the like. The front end of each strap 33 is connected with the front transverse tilt hoop and the rear end of each strap 33 is connected with the 15 rear rim or edge of the hood (Fig. 1).

The hinge 22 which connects the longitudinal tilt hoops 20 and 21 with one another consists (Figs. 7-10) of flat hinge-members 34 connected by screws with sleeves 35 which 20 are flattened on their top face (Fig. 9) and can be turned on pivots 36 connected by U-shaped members 37 with the tilt-hoops 20 and 21. Nuts 38 locked by split-pins hold the sleeves 35 securely in place upon the 25 pivots 36. 39 denotes abutment ledges provided on the sides of the tilt-hoops 20 and 21 (Fig. 8); the ends of said ledges project and serve as abutments for the lateral faces of the sleeves 35 when these latter are in 30 their upper and lower end-positions.

The manner of operation of the entire arrangement and combination of parts described is as follows:

While the hood is in its open position the 35 longitudinal tilt hoop 20 and the longitudinal tilt hoop 21 which forms an extension of the former is carried by the bell-crank lever 17, without any other support, said lever being rigidly connected by the levers 16, 6, 7 40 with the member 8 of the rule-joint or coach-joint 8, 10. To collapse the hood it is sufficient to lift the front longitudinal tilt hoop, the scissors formed by the members 23, 24 being thereby opened and this motion is 45 transmitted to the rule-joint or coach-joint 8, 10 by the bar 15 and the angular member 13. The rule-joint or coach-joint is thereby bent, as shown in Fig. 3, by the telescope-tube spring 12 whereby its member 8 is 50 moved to the rear. The supporting column 5 and the member 13 connected therewith participate in that movement in that they are actuated by the connecting link 7 and the bell-crank lever 6, the member 13 turning 55 on its pivot or hinge 14. Owing to this turning of this member and to the simultaneous turning of the members 8, 10 the bell-crank lever 6, the rods 16 and the bell-crank lever 17 connected therewith are moved 60 in such a manner that the longitudinal tilt hoop 20 is drawn rearwards, but is held fast during this time in horizontal position. It is, therefore, not possible that the front end 65 of the tilt hoop 20 can (as with the known devices) turn downwards and knock upon

the side-parts of the carriage body whereby these parts can be damaged and, besides, special auxiliary means must be provided to open and close the hood. On pressing the hood further rearwards the longitudinal tilt hoop 21 is turned down upon the tilt hoop 20 and moved down upon the body-member 18 which then rests upon the column 5. In the space below this latter the bent rule-joint or coach-joint 8, 10 and the member 13 are received.

Collapsing the hood rearwardly is effected in the most convenient manner by pulling rearwardly the strap or straps 33 after the front longitudinal tilt hoop has been lifted. The hood tarpaulin falls freely rearwards when the tilt hoops are being caused to collapse and can be rolled up and attached to the carriage by the strap or straps 33 or by any other suitable means.

Concerning especially the manner of operation of the hinge-connection between the longitudinal tilt hoops 20 and 21 the following explanations will facilitate understanding it.

If the hinge-members 34 which are screwed together with the sleeves 35 are situated above the tilt hoops it is possible to turn the front tilt hoop towards the rear one on the hinge 22. If, however, the sleeves 35 are turned together with the hinge-member 34 through 180° on the pivots 36 so that the hinge 22 then lies below the tilt hoops, the arrangement and combination of the parts described prevents the hinge 22 from bending through downwardly which is very important and one of the characteristic features of the invention. As the entire hood construction is carried freely by the lever 17 no middle supporting column is any more necessary. The lateral abutment ledges 39 facilitate the adjustment of the hinge members 34 in its two end-positions.

The technical advantages attained by the invention consist essentially therein that the longitudinal tilt hoops are guided parallelly without separate supporting columns when the hood is opened and closed, and are carried rearwards so far that the carriage body windows are not obstructed by the body members 18, in consequence whereof the occupants of the carriage have, when the hood is collapsed, a more unobstructed view than with the known hood supports employed in connection with motor-carriges, also from the reason, as no middle supports are necessary, as already stated. The longitudinal tilt hoops are carried freely owing to the existence of their particular lever connection 8, 7, 6, 16, 17, and they are secured against bending through by the hinge-joint 22, in connection with the parts denoted 34-38.

The lever connection 7, 6, 16 ensures the parallel guiding of the longitudinal tilt

hoops when the hood is opened and collapsed, so that the front end thereof cannot fall down.

Finally, opening and closing the new hood-supporting structure can be effected easily by only one attendant as, owing to the automatic bending through of the rule-joints or coach-joints 8, 10 when the front longitudinal tilt hoops are lifted, it is no more necessary to bend them through manually so that a pull from the rear exerted on the straps 33 is sufficient to collapse the hood. Re-closing it is assisted effectually by the telescope-tube springs 12 which when the hood is collapsed are put under a tension of such strength that they, after having got past the position shown in Fig. 4, tend to lift the hood and to open it.

I claim:

1. A collapsible hood for motor vehicles, comprising an angular column pivoted to the rear part of the vehicle body, a body member rigidly connected to said angular column, two pivotally connected members forming a bipartite coach joint, one member of the coach joint being pivoted to the rear part of the vehicle body, the other member of coach joint being pivoted to the upper end of the angular column, a bell crank lever pivoted to said body member, a rear tilt hoop connected to one arm of said bell crank lever, a second bell crank lever pivoted to said angular column, a link connecting one arm of the second bell crank lever to one member of said bipartite coach joint, and a rod connecting the second arm of the first bell crank lever to the second arm of the second bell crank lever.

2. A collapsible hood for motor vehicles, comprising an angular column pivoted to the rear part of the vehicle body, a body member rigidly connected to said angular column, two pivotally connected members forming a bipartite coach joint, one member of the coach joint being pivoted to the rear part of the vehicle body, the other member of coach joint being pivoted to the upper end of the angular column, a bell crank lever pivoted to said body member, a rear tilt hoop connected to one arm of said bell crank lever, a second bell crank lever pivoted to said angular column, a link connecting one arm of the second bell crank lever to one member of said bipartite coach joint, a rod connecting the second arm of the first bell crank lever to the second arm of the second bell crank lever, a front tilt hoop, a hinge member connecting said tilt hoops with one another and including a rotary sleeve.

bell crank lever, a transverse tilt hoop, an angular member carrying said transverse tilt hoop and being pivotally connected with said angular column, a telescope-tube pivoted at its ends to the lower member of the coach joint and to the said angular member respectively and a spring within said tube.

3. A collapsible hood for motor vehicles, comprising an angular column pivoted to the rear part of the vehicle body, a body member rigidly connected to said angular column, two pivotally connected members forming a bipartite coach joint, one member of the coach joint being pivoted to the rear part of the vehicle body, the other member of coach joint being pivoted to the upper end of the angular column, a bell crank lever pivoted to said body member, a rear tilt hoop connected to one arm of said bell crank lever, a second bell crank lever pivoted to said angular column, a link connecting one arm of the second bell crank lever to one member of said bipartite coach joint, a rod connecting the second arm of the first bell crank lever to the second arm of the second bell crank lever, a front tilt hoop, a hinge member connecting said tilt hoops with one another and including a rotary sleeve.

4. A collapsible hood for motor vehicles, comprising an angular column pivoted to the rear part of the vehicle body, a body member rigidly connected to said angular column, two pivotally connected members forming a bipartite coach joint, one member of the coach joint being pivoted to the rear part of the vehicle body, the other member of coach joint being pivoted to the upper end of the angular column, a bell crank lever pivoted to said body member, a rear tilt hoop connected to one arm of said bell crank lever, a second bell crank lever pivoted to said angular column, a link connecting one arm of the second bell crank lever to one member of said bipartite coach joint, a rod connecting the second arm of the first bell crank lever to the second arm of the second bell crank lever, a front tilt hoop, a hinge member connecting said tilt hoops with one another; and including a rotary sleeve; and an abutment ledge on at least one of said tilt hoops adapted to be engaged by said rotary sleeve in certain of its positions.

In witness whereof, I have hereunto signed my name.

CURT WILLIBALD ALEXIS HANNEBOHN.
